UNITED STATES PATENT OFFICE.

GERALD W. HART, OF WEST HARTFORD, CONNECTICUT, ASSIGNEE TO THE HART MANUFACTURING COMPANY, OF HARTFORD, CONNECTICUT, A CORPORATION OF NEW JERSEY.

ELECTRIC RANGE.

Application filed June 5, 1922. Serial No. 565,907.

To all whom it may concern:

Be it known that I, GERALD W. HART, a citizen of the United States, residing at West Hartford, county of Hartford, State of Connecticut, have invented a certain new and useful Improvement in Electric Ranges, of which the following is a full, clear, and exact description.

My invention relates to electric ranges, and has for its object to provide an electric range having novel and improved features.

The following is a description of the preferred embodiment of my invention, reference being had to the accompanying drawings, in which,—

Figure 1 is an elevation, partly broken away, of a portion of the front of an electric range embodying my invention; and

Fig. 2 is a sectional view, partly in elevation, taken on the line 2—2 of Fig. 1.

The electric range illustrated in the drawings is provided with a top 2; a dial or face plate 4 which is inclined forwardly from its upper edge and has its upper edge arranged adjacent the top 2; and an opening below the face plate closed by a removable closure which in the present embodiment is the front wall of a drip pan 6 having a horizontal bottom wall 8, and a vertical front wall 10 having its upper edge arranged adjacent the lower edge of the face plate when the drip pan is closed, the drip pan being mounted to slide forwardly from the range. The inclination of the face plate 25 enables the plate to be conveniently seen by a person standing in front of the range and the vertical closure 10 results in a desirable configuration for the front of the range.

The illustrated range embodying my invention is also provided with a plurality of rotary snap switches 12, of which there are a number of makes upon the market, for controlling the heating elements of the range. The switches are provided with operating spindles 14 that extend through apertures in the face plate and have arrow shaped thumb pieces 16 secured on their outer ends and adapted to be rotated over the front of the face plate. The switches 50 12 are mounted on the upper portions of blocks 18 of porcelain or other insulating material which are secured on a supporting plate 20 projecting from the top 2 of the range and spaced back of the face plate. 55 The supporting plate 20 is arranged paral-

lel to the face plate 4, and said upper portions of the blocks are arranged parallel with the face plate so that the axes of the switches 12 are arranged perpendicular to the face plate, thus enabling the thumb 60 pieces 16 to be rotated properly over said plate.

To provide for the fuse plugs which are usually employed in electric ranges the switch blocks 18 are extended vertically 65 downward below said switch supporting portions and behind the closure 10, and the front surfaces 22 of this lower portion of the blocks are arranged opposite and parallel to the vertical closure. Said lower portions 70 of the blocks are provided with sockets 24 in which fuse plugs 26 are mounted, the sockets opening out through and having their axes perpendicular to the vertical surface portions 22 of the switch 75 blocks. With this construction it will be apparent that the end faces of the fuse plugs are directed toward the closure 10 so that they are conveniently accessible to view upon opening the closure thus making it 80 unnecessary to remove the plugs in order to inspect them and rendering them easy of access for the purpose of removal and replacement.

What I claim is:

1. An electric range having, in combination, a face plate inclined rearwardly from its lower edge, a movable closure arranged in a substantially vertical plane and adjacent the lower edge of the face plate when in closed position, a block spaced back of said face plate and said closure and having its upper portion arranged opposite and substantially parallel to said face plate, and its lower portion arranged opposite and substantially parallel to said closure, said lower portion of the block having a socket for a fuse plug opening out through and having its axis substantially perpendicular to the front face of said lower portion, a rotary 100 snap switch mechanism mounted on said upper portion of the block and having its operating means extending through said face plate, and a fuse plug mounted in said socket.

2. An electric range having, in combination, a face plate inclined rearwardly from its lower edge, a movable closure arranged in a substantially vertical plane and adjacent the lower edge of the face plate 110

when in closed position, a block spaced back of said face plate and said closure and having its upper portion arranged opposite and substantially parallel to said face plate, and 5 its lower portion arranged opposite and substantially parallel to said closure, said lower portion of the block having a socket for a fuse plug opening out through and having its axis substantially perpendicular to the 10 front face of said lower portion, a rotary

snap switch mechanism mounted on said upper portion of the block and having its operating means extending through said face plate, and a fuse plug mounted in said socket, said vertical closure having a rearward extension and means for supporting the same so that it slides horizontally in moving from closed to open position and vice-versa. 15

GERALD W. HART.
